GROCERY CUPBOARD

Axel Teodor Assmundsson, Goteborg, Sweden

Application March 29, 1946, Serial No. 658,105
In Sweden April 5, 1945

5 Claims. (Cl. 312—270)

1

This invention refers to cupboards for the storage of groceries or such like especially adapted to the needs of private homes where supplies of groceries such as flour of various grains, coffee, dried fruits, sugar, different kinds of spices etc. are kept in quantities necessitated by the regular requirements of cooking in a home.

The main object of the invention is to provide a cupboard which is simple in construction with a minimum of dust collecting corners, easy to clean and easy to fit into different spaces of a kitchen.

Another object of the invention is to provide a cupboard the drawers of which are airtight, thus being suitable for aromatic groceries.

Other objects will appear hereinafter.

The invention consists in the novel combination and arrangement of the drawers in a cupboard hereinafter described and claimed.

The invention will be more readily understood by reference to the accompanying drawing, in which:

Fig. 1 is an elevational view of a cupboard in one embodiment;

Fig. 2 is a cross section thereof;

Fig. 3 is a cross sectional view of a cupboard in another embodiment, and

Fig. 4 a similar sectional view in a third embodiment;

Figs. 5 and 6 are longitudinal sections of portions of cupboards in two further embodiments;

Fig. 7 is an elevation view of a modified cupboard;

Fig. 8 is a cross section thereof in one embodiment, and

Fig. 9 a similar section thereof in another embodiment.

In the drawing, cupboard 1 in Fig. 1 is provided with a number of compartments 2, each compartment containing a row of scoop-like drawers 3. These drawers are supported above the bottom of the compartment in a hanging position against the ceiling 4 by means of cross-directed guides 5 reaching downwards from the ceiling and having T- and L-profiles in coaction with corresponding side flanges 6 of the drawers. Although only three drawers are shown in the compartment this is intended to contain any number of drawers, and when the drawers are removed the compartment being without partition walls will be free for inspection and cleaning with a minimum of dust collecting corners.

Figs. 2-6 show different means of supporting the drawers above the bottoms of the compartments, the drawers in Figs. 2, 3, 5 and 6 in a hanging

2

position against the ceiling. The common feature for the arrangements of the drawers in Figs. 1-5 is that the drawer in its inserted position will be pressed upwards against the ceiling thus preventing air from entering the upturned opening of the drawer covered by the ceiling.

In Fig. 2 the guide 5 is directed inwards and upwards, and the corresponding flange 6 of the drawer shown with dotted lines has the same sloping direction. When the drawer is pushed into the compartment the side flanges of the drawer will slide upwards on the guides and the drawer will move parallel with itself until the upper border surrounding the opening of the drawer stops against the ceiling tightly pressed against the same.

In Figs. 3-5 the means pressing the drawer upwards consist of springs. In Figs. 3 plate springs 7 are placed between the supporting surface of the guide 5a and the bottom surface of the flange. The guide has the same profile as in Fig. 1, but the guide and the drawer flanges have preferably horizontal direction. The spring is attached to the guide but can with the same effect be attached to the flange of the drawer.

In Fig. 4 a plate spring 8 is placed between the bottom of the drawer and the bottom of the compartment. The spring is shown attached to the compartment bottom but can with the same effect be attached to the drawer. In Fig. 5 the guides 9 have in cross section the shape of an inverted V and are provided with foot flanges 10 underlying the flanges of the drawers. The guides are of flexible material as steel or such like, and in a slack state the V is more open as seen at the left side of the figure. When the drawers are inserted the legs of the V are pressed towards each other and the foot flanges 10 will press the drawer upwards against the ceiling. For the outer drawers the V-shaped guide can be replaced by L-shaped guides 9a as seen at the right side of the figure.

In Fig. 6 the guides 11 are formed by dovetail-shaped grooves 12 in the ceiling and the side flanges of the drawers are correspondingly modified to sloping side portions 13.

Fig. 7 shows a simplified embodiment of the cupboard. In this arrangement there is one row only of scoop-like drawers 3 all of them having a common cover 14. This cover consists of a board provided with means as ears 15 and as shown in Fig. 9, with support-rails 16, flanges 17 or such like in order to make the fastening of the same possible in different places in a kitchen for instance to the wall 18 as shown in

Fig. 8, beneath the bottom of an ordinary kitchen cupboard 19 fixed to the wall 18 above the floor as shown in Fig. 9, or to be inserted as a board in such a cupboard etc. The drawers are arranged in a hanging position with respect to the cover and the means for supporting the drawers are the same as shown in the previous figures. In Fig. 8 the same supporting guides 5 are shown as in Fig. 2, and in Fig. 9 the same guides 5a as in Fig. 3, the spring being omitted in this modification. However all the spring arrangements can also be used except the one in Fig. 4.

To prevent the drawer 3 in Fig. 9 from being inserted too far, the flanges 6 of the drawer are provided with rear down-directed projections 20 in coaction with the end of the guides. For cupboard drawers of this kind shoulders or vertical flanges at the handle end of the drawers have hitherto been used for the same object, but when the drawers are made of glass or porcelain these shoulders have a tendency to break. Said projections 20 remove this inconvenience and make the shoulders unnecessary.

While I have illustrated and described the preferred form of construction for carrying my invention into effect, this is capable of variation and modification without departing from the spirit of my invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. A storage bin including the combination of an upwardly open movable receptacle having a front wall, a rear wall and two side walls, stationary support means, a stationary cover plate with a plane under-surface for said receptacle forming part of said stationary means, and cooperative rail and flange means respectively secured to said stationary support means and said receptacle, said rail and flange means being inclined at relatively the same angle downwards and towards the front wall of the receptacle so that said receptacle may be moved in positions parallel to itself, the upturned edge surfaces of all the walls of the receptacle being in flush with each other and forming an unbroken surface surrounding the upturned opening of the receptacle, said unbroken edge surface at the insertion of the receptacle coming to a substantially airtight pressure contact against the plane under surface of the cover plate at the innermost position of the receptacle, the under surface of the cover plate being the sole stopper for the inward movement of the receptacle.

2. A closet including the combination of a closed compartment having an open front and a top with a plane under surface, an upwardly open receptacle having a front wall, a rear wall and two side walls, said receptacle being movable into and out from said compartment through the open front thereof, and cooperative rail and flange means respectively secured to said compartment and said receptacle, said rail and flange means being inclined at relatively the same angle downwards and towards the front wall of said receptacle so that the receptacle may be moved in positions parallel to itself, the upturned edge surfaces of all the walls of the receptacle being in flush with each other and forming an unbroken surface surrounding the upturned opening of the receptacle, said unbroken edge surface at the insertion of

5 the receptacle coming to a substantially airtight pressure contact against the plane under surface of the top at the innermost position of the receptacle, the under surface of the top being the sole stopper for the inward movement of the receptacle.

3. A storage bin including the combination of an upwardly open movable receptacle having a front wall, a rear wall and two side walls, stationary support means, a cover plate with a plane under surface for said receptacle forming part of said stationary support means, substantially continuous rail forming guide means depending from said cover plate, and cooperative substantially continuous flange forming guide means secured on said receptacle, said rail forming guide means and flange forming guide means being inclined at relatively the same angle downwards and towards the front wall of the receptacle so that said receptacle may be moved in positions parallel to itself, the upturned edge surfaces of all the walls of the receptacle being in flush with each other and forming an unbroken surface surrounding the upturned opening of the receptacle, said unbroken edge surface at the insertion of the receptacle coming to a substantially airtight pressure contact against the plane under surface of the cover plate at the innermost position of the receptacle, the under surface of the cover plate being the sole stopper for the inward movement of the receptacle.

4. A storage bin including the combination of an upwardly open movable receptacle having a front wall, a rear wall and two side walls, a cover plate with a plane under surface for said receptacle, means for attaching said cover plate to a stationary support, and cooperative rail and flange means respectively secured to said cover plate and said receptacle, said rail and flange means being inclined at relatively the same angle downwards and towards the front wall of the receptacle so that said receptacle may be moved along a forwardly downwardly inclined path in positions parallel to itself, the upturned edge surfaces of all the walls of the receptacle being in flush with each other and forming an unbroken surface surrounding the upturned opening of the receptacle, said unbroken edge surface at the insertion of the receptacle coming to a substantially airtight pressure contact against the plane under surface of the cover plate at the innermost position of the receptacle, the under surface of the cover plate being the sole stopper for the inward movement of the receptacle.

5. A closet including the combination of a closed compartment having an open front and a plane under surface of the top, a plurality of upwardly open movable receptacles, each having a front wall, a rear wall and two side walls, and cooperative rail and flange means respectively secured to the top of said compartment and the sides of each of said receptacles for supporting said receptacles in said compartment in spaced relationship from its bottom, said rail and flange means being inclined at relatively the same angle downwards and towards the front walls of said receptacles so that each receptacle may be moved along a forwardly downwardly inclined path in positions parallel to itself, the upturned edge surfaces of all the walls of each receptacle being in flush with each other and forming an unbroken surface surrounding the upturned opening of the receptacle, said unbroken edge surface at the insertion of the receptacle coming to a substantially airtight pressure contact against the plane under surface

5

of the corresponding portion of the top at the innermost position of the receptacle, the under surface of the top being the sole stopper for the inward movement of all the receptacles.
